US00D955677S

(12) **United States Design Patent** (10) **Patent No.:** **US D955,677 S**
Chen (45) **Date of Patent:** **** Jun. 21, 2022**

(54) **TOUCH BIN**

(71) Applicant: **EKO DEVELOPMENT LTD.**,
Guangzhou (CN)

(72) Inventor: **Yizhi Chen**, Guangzhou (CN)

(73) Assignee: **EKO Development Ltd.**, Guangdong
(CN)

(**) Term: **15 Years**

(21) Appl. No.: **29/753,352**

(22) Filed: **Sep. 30, 2020**

(51) LOC (13) Cl. **09-09**

(52) U.S. Cl.

USPC **D34/7**

(58) **Field of Classification Search**

(57) **CLAIM**

The ornamental design for a touch bin, as shown and described.

DESCRIPTION

FIG. 1 is a perspective view of a touch bin, showing my new design.

FIG. 2 is a top plan view thereof.

FIG. 3 is a left-side elevation view thereof.

FIG. 4 is a front elevation view thereof.

FIG. 5 is a right-side elevation view thereof.

FIG. 6 is a bottom plan view thereof; and,

FIG. 7 is a rear elevation view thereof.

The broken lines in the drawings depict portions of the touch bin that form no part of the claimed design.

1 Claim, 7 Drawing Sheets
